UNITED STATES PATENT OFFICE.

GEORGE S. JOHNSTON, OF CHICAGO, ILLINOIS, ASSIGNOR TO GEO. S. JOHNSTON COMPANY, OF CHICAGO, ILLINOIS, A CORPORATION OF ILLINOIS.

GOOGLES.

Original application filed September 15, 1919, Serial No. 323,990. Divided and this application filed February 27, 1920. Serial No. 361,829.

To all whom it may concern:

Be it known that I, GEORGE S. JOHNSTON, a citizen of the United States, residing at Chicago, in the county of Cook and State 5 of Illinois, have invented certain new and useful Improvements in Goggles, of which the following is a specification.

The present invention has to do with improvements in goggles that may be applied 10 to various uses, but more particularly the invention concerns a novel and improved form of goggle frame and guard associated therewith which is of strong and simple construction and permits of the glasses 15 or lenses being readily withdrawn or replaced as required.

The features of the present invention are susceptible of embodiment in a number of different forms, certain of which are illustrated in the drawings. Accordingly, the objects and purposes of this invention may best be understood from the specification to follow wherein reference is made to the accompanying drawings which exhibit the invention in two different constructions in the following manner:

Figure 1 is a plan view of one form of goggle embodying the features of the present invention;

Fig. 2 shows a front elevation thereof; Fig. 3 shows a longitudinal section taken on the line 3—3 of Fig. 1, looking in the direction of the arrows;

Fig. 4 shows one of the goggle eyes or bows with its associated parts removed;

Fig. 5 shows a transverse section taken on the line 5—5 of Fig. 1, looking in the direction of the arrows;

Fig. 6 shows a plan view of a modified 40 form of goggle;

Fig. 7 shows a front elevation corresponding to Fig. 6;

Fig. 8 shows a longitudinal section taken on line 8—8 of Fig. 6, looking in the direction of the arrows;

Fig. 9 exhibits one of the goggle eyes or bows of the construction shown in Figs. 6, 7, and 8; and

Fig. 10 shows a transverse section taken 50 on the line 10—10 of Fig. 6, looking in the direction of the arrows.

The frames and guards of the devices that will now be described in detail are prefer-

ably constructed of some light, strong, and suitable material, such, for instance, as fibre 55 or any serviceable composition that possesses the properties requisite for this invention.

I will first describe the construction shown in Figs. 1 to 5 inclusive. In this 60 case a frame is employed consisting of two parts each in the form of a bow or eye 11, and each having a bridge piece 12 that is adapted to co-operate with the bridge piece of the other when resting on the nose of 65 the wearer. The two parts of the frame are shown as flexibly connected by means of a strap 13.

According to the construction now being described each bow is arranged to extend 70 around the edge of a crystal or lens for 180 degrees or less, and is provided near each of its ends with a slit or cut 14 on the outer side thereof. The construction of the two members is identical so that the same reference numerals have been applied to the corresponding parts of each.

The mounting of the crystals or lenses in this goggle is so arranged or constructed as to permit them to be readily attached or 80 detached relative thereto, and to hold them immovably in place thereon. For this purpose, I employ a guard 15 of suitable form to properly exclude the light and particles from the eyes of the wearer, and also to 85 provide a cylindrical portion designated 16 which is suitably channeled as at 17 to retain in place a crystal or lens 18. As a means of entry or withdrawal of the lens or crystal an elongated opening 19 is ar- 90 ranged in the guard in line with the channel 17 having a length substantially the same as the arc of the bow 11, so that in assembled relationship the ends thereof rest adjacent to the ends of the opening 19. A 95 curved clip 20 is also employed having at each of its ends an inturned catch 21 adapted to spring in position within the slits or cuts 14 and remain in place therein. Each guard may be equipped with a suitable cord 100 or strap adapted to connect with the other when passed around the head of the wearer so as to hold the goggle in place, this arrangement being suggested merely as a convenient means for this purpose.

In assembling the crystals or lenses into

the present goggle construction, the guards are first removed so as to allow the crystals to be slipped into place through the openings 19. Each guard is then arranged adjacent to its bow 11, and thereafter the clip 20 is snapped into place. When the parts have thus been operatively engaged, the two ends of the bow will abut the ends of the opening 19, its intermediate curved portion conforming generally to that of the crystal. When the clip 20 is applied in place by snapping its ends 21 into locking relation with the slits or cuts 14, the guard is locked immovably to the frame. This same locking relation serves also to prevent movement of the crystal within the guard. It is obvious that a withdrawal of the crystal from the guard may be effected by a reversal of the operations described.

I will now describe the construction shown particularly in Figs. 6 to 10 inclusive. In this case a frame is employed consisting of two parts each in the form of a bow or eye 22 having a bridge piece 23 that is adapted to co-operate with the bridge piece of the other when resting on the nose of the wearer. The two parts of the frame are shown as flexibly connected together by means of a strap 24. According to the present construction each bow is arranged to extend around the edge of a crystal or lens for 180 degrees or less, and is provided near one of its ends with a notch 25 on the inner side and near the opposite end with a slit 26 on its outer side.

The mountings of the lenses or crystals in this goggle is so arranged and constructed as to permit them to be readily attached or detached relative thereto, and to hold them immovably in place thereon. For this purpose I employ a guard 27 of suitable form and shape to exclude light and particles from the eyes of the wearer and provided with a cylindrical portion 28 which is suitably channeled as at 29 to hold in place a crystal or lens 30. As a means of entry or withdrawal of the crystal an elongated opening 31 is arranged in the guard in line with the channel 29 having a length substantially the same as the arc of the bow 22 so that in assembled relation the ends thereof may rest adjacent to the ends of the opening 31. A second and shorter opening 32 slightly spaced from the elongated opening 31 and separated therefrom by a web 33 is arranged to receive the end of the bow 33 adjacent to the notch 25 which constitutes in effect a hook adapted to co-operate with the opening 32. By this arrangement a connection is established between the guard and frame at one end of the bow. On the opposite end of the bow another connection is provided consisting of a spring 34 secured to the guard at one end as at 35 and having its opposite end turned as at 36 to provide

a catch 37 which is adapted to operate with the cut or slit 26. The tendency of the spring is always to snap towards the bow, so that when the parts are assembled in the manner described, the catch of the spring will automatically enter into locking relation with the proximate end of the bow to hold the guard immovably in the frame and to prevent movement of the crystal within the guard. It is obvious that a withdrawal of the crystal from the guard may be effected by the reversal of the operations described.

The two forms of goggle illustrated and which have now been described in detail are simple in their construction and render facile a substitution of crystals or lenses whenever this may be desired. In addition these constructions securely hold the crystals in place, and prevent the entrance of particles of dust and the like around them. Obviously the invention is susceptible of embodiment in other forms than the ones herein suggested, and in respect of any changes or modifications that may utilize the principles of this invention, as described in the claims below, I desire that they should be included within the scope of this patent.

This application is a division of my co-pending application for Letters Patent of the United States Serial No. 323,990, filed by me September 15, 1919.

I claim:

1. A pair of goggles comprising in combination two eye guards each having its inner edge of contour suitable to seat against the face of the wearer and each having near its outer edge an annular interior groove for the accommodation of the edge of a crystal, there being a semi-circular slot at the inner side of each said groove giving access thereto and permitting the introduction or removal of the crystal, a crystal seated within each said groove, a semicircular frame adjacent to each said slot and having its end portions adjacent to the ends of the slot, and having a locking slit at the end of one said end portion, and spring means on the eye guard and engaging the slit of the frame to thereby hold the frame in position adjacent to the guard whereby the frame and guard may be engaged and disengaged by flexion of the spring means and without necessary flexion of the frame, substantially as described.

2. A pair of goggles comprising in combination two eye guards each having its inner edge of contour suitable to seat against the face of the wearer and each having near its outer edge an annular interior groove for the accommodation of the edge of a crystal, there being a semi-circular slot at the inner side of each said groove giving access thereto and permitting the introduction or re-

moval of the crystal, a crystal seated within each said groove, a semi-circular frame closing each said slot and having its end portions adjacent to the ends of the slot, there being a locking slit in the end portion of one end of each said frame, and a spring on the guard adjacent to said end of the frame, and adapted to engage the slit of the frame whereby the frame and guard may be engaged and disengaged by flexion 10 of the spring means and without necessary flexion of the frame, substantially as described.

GEO. S. JOHNSTON.
